UNITED STATES PATENT OFFICE.

KNUT S. KNUTSON, OF DENVER, DAKOTA TERRITORY.

HORSE-POWER.

SPECIFICATION forming part of Letters Patent No. 313,214, dated March 3, 1885.

Application filed November 21, 1884. (No model.)

To all whom it may concern:

Be it known that I, KNUT S. KNUTSON, of Denver, in the county of Kingsbury and Territory of Dakota, have invented certain new and useful Improvements in Driving-Wheels; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention has for its object to provide a portable horse-power of a simplified and novel construction, which allows the power-shaft or tumbling-rod to come nearer the ground, and which shall occupy less space and secure a lighter draft than the ordinary horse-powers now in use; and my improvements consist, essentially, in the details of construction and general arrangement of parts, all as will be hereinafter fully described, and specifically designated in the claim.

In the accompanying drawings, Figure 1 represents a top plan view of my invention; Fig. 2, a vertical longitudinal section, and Fig. 3 a detail bottom view thereof.

Similar letters of reference occurring on the several figures indicate like parts.

Referring to the drawings, A represents the main frame of my invention, which is similar in shape to that of an ordinary wagon-frame, and provided with axles A' at each end for the reception of suitable wheels. The master-wheel or driving-disk B is mounted upon the top of the main frame A, and is supported upon friction rollers or wheels a, journaled in suitable bearings, a', upon the sides of said frame, as fully shown in Fig. 3. Suitable guide-wheels, b, journaled in bearings projecting from the ends of the cross-frames A², are adapted to run in the circular track B' of the master-wheel B, to hold the same in proper position upon the frame at all times.

C C' represent two vertical shafts journaled one at each end of said frame in suitable bearings, as shown. To the upper ends of each of these vertical shafts C C' is secured a cog-wheel, D, which meshes with the cogs of the master or driving wheel B, while near the lower ends of said shafts are affixed the bevel-gears E E', which communicate motion to the power-shaft or tumbling-rod F through the medium of the bevel-pinions

c c', affixed to said power-shaft, as fully shown in Figs. 2 and 3.

Through the central cross-frame, A³, is journaled a brake-rod, d, carrying a wheel, d', upon its upper end, and having two chains, 60 e, attached to its lower end, which are in turn connected to the upper ends of gripping or toggle jaws G, which are arranged to fit around the grooved wheel F' upon the central part of the tumbling-rod F in such manner that the speed of the apparatus can be checked or controlled at will through the medium of the brake-wheel d'.

The master-wheel or driving-disk B is provided with suitable bearings for the draft-poles H, and said wheel being extended outwardly from the main frame insures a direct and light draft, being reliable in action, and occupying but little space.

When the apparatus is in operation, the vehicle-wheels of the main frame A, unless they are small in diameter, are removed, thereby bringing the power-shaft or tumbling-rod close to the ground, thus obviating the liability of the horse stumbling over the same, 80 as is often the case when the power-shaft or tumbling-rod stands up high from the ground.

The apparatus may be readily moved from one place to another, and is designed for any of the various purposes to which a horse-power is applicable. A protecting plate or cover, I, may be used to cover the cog-gearing of the driving-wheel and vertical shafts to prevent the lodging of dirt or refuse therein.

Having thus described my invention, what I claim as new and useful is—

The herein-described horse-power, consisting of the frame A, provided with cross-frames A² A³ and axles A', driving-wheel B, secured in place upon said frame between the friction rollers or wheels a and b, vertical shafts C C', provided with cog-wheels D and bevel-gears E E', power-shaft F, provided with bevel-pinions c c' and friction-wheel F', and the gripping mechanism G, all substantially 100 as and for the purpose specified.

In testimony that I claim the foregoing as my own I affix my signature in presence of two witnesses.

K. S. X KNUTSON.
